JAMES J. KUSIV, OF NEWARK, NEW JERSEY

PAPER TRIMMER

Application filed January 24, 1930. Serial No. 423,148.

The present invention relates to an improved cutter or trimmer for use in severing paper, cloth or similar sheet material and the primary object of the invention is to provide 5 an improved cutter or trimmer for severing sheet material thru a mere forward sliding motion of the device.

A further object of the invention is to provide an improved paper trimmer or cutter 10 which will greatly expedite cutting and trimming of sheet material with little or no effort upon the part of the operator.

A further object of the invention is to provide a device of this character which will 15 sever the material on a straight clean cut line.

A still further object of the invention is to provide an improved paper trimmer embodying a pair of elongated runner bars between 20 which the paper is disposed during the severing operation, and having means for guiding the parted edges of the paper in a straight line parallel to the longitudinal axis of the runner bars.

A still further object of the invention is 25 to provide a novel and efficient device of this character whereby new or discarded safety razor blades may be employed as the cutting device.

A still further object resides in the novel 30 construction of the device permitting of the same being formed from relatively simple stampings.

Other objects and advantages of the invention will be apparent during the course 35 of the following detailed description, taken in connection with the accompanying drawings forming a part of this specification and in which drawings:

Figure 1 is a side elevation of the trimmer 40 and showing the same in condition for use.

Figure 2 is a side elevation showing the lower runner bar or foot swung downwardly.

Figure 3 is a vertical longitudinal section 45 thru the trimmer.

Figure 4 is a top edge view of the trimmer.

Figure 5 is a section on line 5—5 of Figure 1.

Figure 6 is a side elevation of a slightly 50 modified form of trimmer and showing a

power driven cutting disc for use in cutting soft or damp sheets of paper, cardboard, tracing cloth or any similar thin sheet material.

Figure 7 is a top plan view of the trimmer 55 shown in Figure 6.

Figure 8 is an enlarged fragmentary section showing the manner of mounting the cutting disc and the drive means therefor.

Figure 9 is a section on line 9—9 of Figure 6.

In the drawings, and wherein similar reference characters designate corresponding parts thruout the several views, the letter A 65 may designate the form of trimmer provided with a fixed cutting blade, and B the form of trimmer provided with a power driven rotary cutting blade.

The trimmer A embodies a main body portion 5 and a minor or foot portion 6 pivotally 70 connected at one end to the body portion 5. The main body portion 5 is preferably formed from a light metal such as aluminum or the like and is preferably constructed from two sections 7 and 8 as shown in Figure 5 secured 75 together by screws or other suitable fastening elements 9'. The companion pair of sections 7 and 8 form the longitudinally divided main body portion 5 and are of such shape as to form an elongated shank portion 9 having at its rear end the upwardly offset and rearwardly extending handle portion 10. The longitudinally divided shank portion 9 is provided with a straight bottom edge 11 and has its forward end beveled and rearwardly inclined as at 12 defining a guide 80 point 13 at the foremost end of the shank portion. As will be observed in Figure 4 this guide point 13 is disposed at the longitudinal center line of the shank portion 9. The forward end of the straight flat bottom edge 11 is curved upwardly at the lower ends 85 of the bevels 12 as at 14 to form the upper wall of a flaring mouth 15 into which the sheet material is guided to be severed by the cutting blade 16.

In the example shown the fastening elements 9' are in the form of machine screws having counter-sunk heads seating flush in the section 8 and having threaded connec- 90

tion with the section 7. Disposed about the shank of the machine screw extending thru the handle portion 10 and the machine screw disposed at the forward end of the shank portion 9 are spacing washers 17 which serve for slightly spacing the sections 7 and 8. Disposed between the intermediate portions of the sections 7 and 8 is a relatively thin shim 18 a portion of which extends below the edge 10 11 forming a guide plate portion 19. This elongated shim 18 is secured in position by the fastening element 9' connecting the intermediate portions of the sections 7 and 8.

The spacing washer 17 between the forward 15 ends of the shank sections and the shim 18 between the rear sections of the shank portion provides a thin slot 20 thru the shank portion in which is received the thin cutting blade 16. The cutting blade 16 in the example shown is a conventional type of double edge safety razor blade and which blades are formed with openings for mounting of the blades in the safety razor holders. It may here be well to state that the shim washers 17 and shim 18 are of a thickness equal to the thickness of the cutting blade 16 so that the thin blade receiving slot 20 will snugly receive the cutting blade.

The shank portion 9 is provided at opposite sides of the blade receiving slot 20 with aligning upwardly and forwardly inclined keyways 21 for receiving the shank of a clamping bolt 22 which projects thru one of the openings in the blade 16 and has threaded thereon a wing nut 23 which when turned tight on the bolt 22 firmly clamps the blade in an inclined position between the shank sections. The blade 16 is disposed in the slot 20 with its forward cutting edge extending in an upwardly and forwardly inclined relation to the axis of the shank portion 9 and with the rear edge of the blade spaced closely adjacent the forward edge of the guide plate portion 19 of the shim 18. The blade 45 16 of course projects below the bottom edge 11 of the shank portion.

A guard 24 may be provided for the upwardly projecting portion of the blade and this guard may be of U-formation having 50 its arms insertable into suitable pockets 25 formed in the confronting surfaces of the shank portion sections adjacent the front and rear edge of the blade receiving slot 20. The guard may be removable or may have 55 its arms clamped in the slot 25. This clamping means for the blade 16 permits adjustment of the blade for disposing new portions of the cutting edge in a cutting position beneath the shank portion 9.

60 It will here be noted that the side surfaces of the flat cutting blade are in direct alignment with the side surfaces of the guide plate portion 19 and that the cutting edge of the blade is in alignment longitudinally of the trimmer with the guide point or tip 13.

The minor or foot portion 6 for co-acting with the shank portion 9 for directing the sheet material to be cut to the cutting blade 16 is also preferably formed of a light metal such as aluminum or the like and is preferably formed in two sections divided longitudinally. The companion sections 27 and 28 are joined by means of machine screws 29 one of which designated at 29' arranged at the rear end portion of the sections extends thru the guide plate portion 19 for pivotally connecting the foot portion to the main body portion 5. A spacing washer 30 is arranged between the forward portions of the sections 27 and 28. The elongated foot portion or 70 runner 6 is formed with a flat upper edge 31 for confronting relation with the flat lower edge 11 of the shank portion 9. The forward end of the runner 6 is tapered as at 32 and projects beyond the forward end of the shank portion 9 so that the upper curvature of the taper co-acts with the curvature 14 for providing the flaring mouth 15. The spacing of the runner sections 27 and 28 by the washer 30 and guide plate 19 forms an 80 opening for receiving the lower end of the blade 16 when the runner is in operative relation to the shank portion 9. The guide plate 19 may be notched at its forward end as at 33 to form a stop shoulder against 90 which the intermediate attaching screw 29 may abut for limiting swinging movement of the runner toward the shank portion 9. This limited movement of the runner 6 forms a shallow guide way 34 between the confronting edges of the portions 6 and 9 thru which 100 the paper moves and is parted by the blade 16.

Formed vertically thru the foot or runner 6 with its upper end disposed at the cutting point of the blade 16 is an opening 35 preferably having a tapering upper end as clearly shown in Figure 3 opening at the flat upper edge 31. This opening 35 serves to carry small particles of paper away from the cutting point of the blade so as to prevent wedging and consequent tearing of the sheet being cut. Downward swinging of the foot 6 to a position as shown in Figure 2 will permit ready removal of clogged paper particles from the blade 16 and guide way 34 and will also permit adjustment and renewing of the blade 16 without removal of the guard 24 disposed over the upper exposed portion of the blade.

120 In use of the improved trimmer it is merely necessary to guide the paper into the flaring mouth 35 and align the guide point 13 with the line on which it is desired to sever the paper. Forward movement of the trimmer then moves the blade into engagement with the paper and as the paper is severed the parted edges will be retained in the straight guide way 34 in engagement with opposite sides of the guide plate 19 so that the trim- 125 130

mer is guided in a perfectly straight path making a clean and straight cut.

Because of the desirability of having the blade 16 and guide plate 19 extremely thin for properly severing the sheet material being cut without rolling the cut edges, it is preferred that the sections 5 and 6 each be formed of companion sections separable on a line longitudinally of the trimmer. This arrangement permits of the steel shim 18 being formed of a thickness no greater than the thickness of the blade 16.

Referring now to the rotary cutter type of trimmer B shown in Figures 6 to 9 inclusive, the trimmer includes the main body portion 40 and the minor or runner portion 41 each of which is preferably constructed from a companion pair of sections divided on a line longitudinally of the trimmer.

In this form of trimmer, a circular cutting blade 42 is mounted between the sections 43 and 44 of a shank portion 45. The sections of the body portion 40 may be secured together by means of suitable machine screws 46.

Journalized at its ends in suitable bushings 47 and 48 mounted respectively in the shank sections 43 and 44 is a shaft 50. Secured by a pressed fit to the central portion of the shaft 50 is a bevel gear 51 fitting in a pocket 52 provided in the inner side of the shank section 43. Fitting also on the shaft 50 in abutting relation with the bevel gear 51 is the cutting disc 42 which is held against rotation on the shaft by means of a preferably round nut 53 having threaded connection upon the shaft. The nut 53 is disposed in a pocket 54 provided at the inner side of the shank section 44. The gear 51 abuts with the bushing 47 and the nut 53 abuts with the bushing 48 for preventing longitudinal shifting of the shaft 50 and retains the cutting disc in alignment at the longitudinal center of the shank portion 45. The cutting disc 42 is of such diameter as to project below the lower edge of the shank portion and extend into the runner 41. It may here be well to state that the runner 41 is of identical construction as that of the runner 6 shown and described in Figures 1 to 5 inclusive.

The portions 40 and 41 are joined by a shim having the depending guide plate portion 56 to which the portion 41 is pivotally connected by the combined pivot and connecting screw 57. Thus it will be seen that the rotary cutting disc 42 is in direct alignment forwardly of the guide plate portion 56. An arcuate guard 58 is preferably disposed over the upper exposed portion of the cutting disc 42 and may be suitably secured at its ends to the shank portion 45.

The gear 51 meshes with a bevel pinion 60 suitably journalized in a bushing 61 thru which a flexible drive shaft 62 extends for connection with the bevel pinion. This flexible drive

shaft 62 extends rearwardly thru the divided handle portion 63 and at the rear end of the handle portion may be suitably connected with a flexible drive shaft 64 operated in any desired manner.

This power driven cutting disc 42 will be found especially well adapted for use in cutting soft paper such as blotting paper, newspaper and the like, and will also be found especially well adapted for cutting damp blue print paper, blotting paper, cardboard, tracing cloth, or any similar thin sheet material.

While both forms of trimmer A and B are primarily intended for use in cutting and trimming blue prints by merely pushing the trimmer along a line on which it is desired to sever the paper, it will readily be apparent that the trimmers may be used for cutting various kinds of sheet material. From the foregoing it will be observed that an improved construction for paper trimmers has been disclosed whereby the paper may be severed on a straight clean cut line without requiring a straight edge or line along which the trimmer may be guided for producing a straight cut. It will also be apparent that with a trimmer such as disclosed, the paper or other sheet material is severed thru merely pushing the device across the paper and permits of the paper being cut in an easy manner.

Changes in detail may be made to the forms of invention herein shown and described, without departing from the spirit of the invention or the scope of the following claims.

I claim:

1. A paper trimmer comprising a main body portion including an elongated shank, an elongated runner disposed in parallel relation beneath the shank, a thin web connecting the rear portions of the shank and runner in slightly spaced apart relation and providing a narrow guide way, and a cutter traversing the guide way between the shank and runner forwardly of the web and having its side surfaces in alignment with the side surfaces of the web.

2. A paper trimmer comprising a main body portion including an elongated shank having a straight under edge, a guide plate depending from the rear lower portion of the shank at the longitudinal center thereof, an elongated runner mounted upon the guide plate and having a straight upper edge parallel to and slightly spaced beneath the straight edge of the shank, and a cutter carried by the shank in alignment at the forward end of the guide plate in alignment longitudinally of the shank with the guide plate.

3. A paper trimmer comprising a main body portion including an elongated shank portion having a straight under edge and a guide point at its forward end at the longitudinal center of the shank portion, a flat guide plate depending from the rear portion

of the shank at the longitudinal center thereof, a runner mounted at its rear portion on the guide plate and having a straight upper edge in closely spaced relation beneath the straight lower edge of the shank portion, and a flat cutting blade extending across the spacing between the shank portion and runner in alignment between the guide point and guide plate.

10. 4. A paper trimmer comprising a main body portion including an elongated shank portion having a straight under edge, said shank portion having a beveled forward end forming a guide point at the longitudinal center of the shank, a flat guide plate carried by and depending from the rear portion of the shank, a runner pivotally connected at its rear end to the guide plate and having a straight upper edge for movement into spaced parallel relation to the lower straight edge of the shank, and an inclined blade extending between the shank portion and runner at the forward end of the guide plate in alignment longitudinally of the trimmer between the guide point and guide plate.

5. A paper trimmer comprising a main body portion including an elongated shank portion having a beveled forward end providing a guide point, a guide plate depending from the rear portion of the shank portion in alignment longitudinally of the shank with the guide point, a runner pivotally connected at its rear end to the rear portion of the guide plate and extending longitudinally beneath the shank portion, said runner having a tapered forward end projecting beyond the forward end of the shank portion, and a cutting blade carried by the shank portion at the forward end of the guide plate in alignment between the guide point and guide plate.

6. A paper trimmer comprising a main body portion including a shank portion, a guide plate depending from the rear portion of the shank portion with its side surfaces in a plane longitudinally of the plate portion, a runner pivotally mounted at its rear portion upon the guide plate for extending longitudinally beneath the shank portion, a cutter carried by the shank portion in alignment forwardly of the guide plate and having its forward cutting edge extending into the runner, and an opening formed thru the runner at the cutting point of the cutting edge.

7. A paper trimmer comprising a main body portion including a shank portion having a straight under edge and a guide point at its forward end at the longitudinal center of the shank portion, a flat guide plate depending from the rear portion of the shank, an elongated runner pivotally mounted at its rear end upon the rear portion of the guide plate and having a straight upper edge for confronting relation with the straight under

edge of the shank portion, means limiting upward swinging movement of the runner toward the shank portion to provide a paper receiving guide way, said guide plate when the runner is in operative relation to the shank portion extending into the runner, and a blade carried by the shank portion at the forward end of the guide plate and extending into the runner, said blade being in alignment between the guide point and guide plate.

8. A paper trimmer comprising a main body portion including an elongated shank portion having a slot vertically therethru at the longitudinal center of the shank, a guide plate depending from the shank portion rearwardly of the slot and in alignment therewith, a runner pivotally mounted at its rear end upon the guide plate for movement into a parallel position beneath the shank portion, a flat blade arranged in said slot in alignment with the guide plate and depending into the runner, and means for adjustably and removably retaining the blade in the slot of the shank portion.

9. A paper trimmer comprising a main body portion including an elongated shank portion having a vertical slot therethru, a plate depending from the shank portion rearwardly of the slot, a runner pivotally connected at its rear end to the plate for extending longitudinally beneath the shank portion, a double edge blade extending thru the slot in alignment with the plate and projecting above and below the shank portion, a guard carried by the shank portion and extending about the upper projecting end of the blade, and a clamping bolt extending thru the shank portion for adjustably and removably retaining the blade in the shank.

10. A paper trimmer comprising a longitudinally divided main body portion including sections forming an elongated shank portion, means connecting the sections in slightly spaced relation, a shim plate connected between the sections at the rear of the shank portion and having a depending portion providing a guide plate, a longitudinally divided runner embodying separable sections pivotally connected at their rear portions to the rear portion of the guide plate, and a cutter mounted between the sections of the shank portion in alignment forwardly of the shim and having its lower end extending between the sections of the runner.

11. A paper trimmer comprising a main body portion including a shank portion and a handle portion, a runner extending longitudinally beneath the shank portion, a thin web connecting the rear portion of the shank to the rear portion of the runner and forming a paper receiving guide way between the shank and runner, a cutting disc rotatably mounted in the shank portion in alignment forwardly of the web, and drive means for

rotating the disc embodying a flexible drive shaft extending longitudinally thru the handle portion.

12. A paper trimmer comprising a main body portion including a shank portion and a handle portion, a runner extending longitudinally beneath the shank portion, a thin web connecting the rear portion of the shank to the runner, a shaft rotatable in the shank portion forwardly of the web, a circular cutting edge affixed to the shaft and disposed in alignment forwardly of the web, a bevel gear affixed to the shaft, a bevel pinion meshing with the bevel gear, said gears being enclosed 19 in a pocket formed in the shank portion, and a flexible drive shaft connected with the bevel pinion and extending rearwardly to the rear end of the handle portion.
